US00D897098S

(12) **United States Design Patent** (10) Patent No.: **US D897,098 S**
(45) Date of Patent: **** Sep. 29, 2020**

(54) CARD HOLDER SET	5,602,924 A	2/1997	Durand et al.
(71) Applicant: MASIMO CORPORATION , Irvine, CA (US)	5,638,816 A	6/1997	Kiani-Azarpayjany et al.
(72) Inventor: Ammar Al-Ali , San Juan Capistrano, CA (US)	5,638,818 A	6/1997	Diab et al.
(73) Assignee: Masimo Corporation , Irvine, CA (US)	5,645,440 A	7/1997	Tobler et al.
(**) Term: 15 Years	5,671,914 A	9/1997	Kalkhoran et al.
(21) Appl. No.: 29/666,520	5,726,440 A	3/1998	Kalkhoran et al.
(22) Filed: Oct. 12, 2018	D393,830 S	4/1998	Tobler et al.
(51) LOC (12) Cl. 03-01	5,743,262 A	4/1998	Lepper, Jr. et al.
(52) U.S. Cl. D3/247	5,747,806 A	5/1998	Khalil et al.
(58) Field of Classification Search	5,750,994 A	5/1998	Schlager
USPC D3/247, 249-253	5,758,644 A	6/1998	Diab et al.
CPC A45C 1/06; A45C 3/08	5,760,910 A	6/1998	Lepper, Jr. et al.
See application file for complete search history.	D406,001 S *	2/1999	Nemeth D6/407
(56) References Cited	5,890,929 A	4/1999	Mills et al.

CLAIM

The ornamental design for a card holder set, as shown and described.

DESCRIPTION

FIG. 1 is a front and side perspective view of a card holder set embodying our new design;
 FIG. 2 is a back and side perspective view thereof;
 FIG. 3 is a front view thereof;
 FIG. 4 is a back view thereof;
 FIG. 5 is a left side view thereof, and the right side view is a mirror image of the left side view;
 FIG. 6 is a top view thereof;
 FIG. 7 is a bottom view thereof;
 FIG. 8 is a reduced-scale front and top perspective view thereof;
 FIG. 9 is a front and side perspective view of the card holder set embodying our new design, where the card is detached from the card holder;
 FIG. 10 is a back and side perspective view thereof;
 FIG. 11 is a front view thereof;
 FIG. 12 is a back view thereof;
 FIG. 13 is a left side view thereof, and the right side view is a mirror image of the left side view;
 FIG. 14 is a top view thereof;
 FIG. 15 is a bottom view thereof;
 FIG. 16 is a front and side perspective view of the card holder embodying our new design;
 FIG. 17 is a back and side perspective view thereof;
 FIG. 18 is a front view thereof;
 FIG. 19 is a back view thereof;
 FIG. 20 is a left side view thereof, and the right side view is a mirror image of the left side view;
 FIG. 21 is a top view thereof;
 FIG. 22 is a bottom view thereof;
 FIG. 23 is a reduced-scale front and top perspective view thereof; and,
 FIG. 24 is a reduced-scale front, bottom, and side perspective view of the card holder embodying our new design.

The broken lines, where shown, are used to illustrate environmental subject matter that form no part of the claimed design.
